W. O. THEWES

PIPE WRENCH

Filed May 26, 1922

William O. THEWES
INVENTOR.

BY *Rickey Slough + Watts*

H.I.S. ATTORNEY.5

UNITED STATES PATENT OFFICE.

WILLIAM O. THEWES, OF RIDGEVILLE, OHIO, ASSIGNOR TO THE RIDGE TOOL COMPANY, OF NORTH RIDGEVILLE, OHIO, A CORPORATION OF OHIO.

PIPE WRENCH.

Application filed May 26, 1922. Serial No. 563,801.

To all whom it may concern:

Be it known that I, WILLIAM O. THEWES, a citizen of the United States, residing at Ridgeville, in the county of Lorain and 5 State of Ohio, have invented certain new and useful Improvements in Pipe Wrenches, of which the following is a full, clear, concise, and exact description, such as will enable others skilled in the art to which it 10 appertains to make and use the same.

More particularly my invention relates to wrenches of the type in which the nut that controls the adjustment of the movable upper jaw is not imprisoned by the wrench 15 frame, but free to travel along the threaded stem of the jaw without the necessity of having the jaw moved.

Heretofore, wrenches of this general character have been made, but have been hampered with sliding springs, the function of 20 which spring is to normally press the upper part of the jaw forward. Furthermore, such springs have been so mounted that the tension against the jaw is not always uniform, and in certain positions, the direction 25 of the tension is reversed.

Among the objects of my invention are—

To provide a wrench of the above general character in which the above objections 30 are eliminated.

Another object is to provide suitable protection for the tension spring.

Another object is to make the tension spring stationary.

I also find that mechanics in using wrenches of this character, are prone to use the same not only for applying pressure to produce rotation in a plane parallel with the width of the wrench, but they also use 35 the wrench by applying pressure to the handle at right angles thereto, as in bending pipes.

One of the objects of my invention is to provide a rugged, substantial wrench which 40 will stand this kind of use, and which will insure against the more delicate parts of the wrench being injured.

Another object therefore of my invention is to provide a wrench in which the casing

through which the sliding jaw moves and 50 the handle are made in one continuous unitary piece, and in which the cross sectional area increases steadily from the tip of the handle toward the head of the wrench, not only in the direction of thickness but in the 55 direction of breadth as well.

To provide other details of improvement to increase the efficiency and serviceability of a wrench of the above general character.

To accomplish the foregoing and other 60 useful ends, my invention makes use of means hereinafter more fully set forth and claimed.

Referreing to the accompanying drawing, Fig. 1, is a side view of the wrench in elevation.

Fig. 2 is a front view of the same.

Fig. 3 is a side elevational view of the spring employed.

Fig. 4 is a plan view of the said spring. 70

Referring more in detail to the accompanying drawing, it will be seen that the handle element 2 tapers gradually toward the head 3 shown in the upper part of the drawing. This head has a heel 4 which, as 75 will be seen, projects to the left in Fig. 1. The tapering referred to takes place along both the dimensions of breadth and thickness as will appear from an inspection of the drawing, Figs. 1 and 2. The object in this construction is to make the instrument rugged so that it may be used for lateral strains as well as strains in the usual direction.

It will be observed that through the heel 85 there extends a channel in which the movable jaw 5 slides. This channel flares upwardly, the throat 6 being on the lower side and being narrower than the mouth 7 which is on the upper side. Within this channel 90 there is a spring 8 which serves to maintain pressure against the jaw 5 tending normally to incline the upper part of the jaw to the right. This spring is mounted just below the protuberance 9 which latter serves to 95 force the spring forward. Just below this protuberance, the spring 8 is secured to the heel by the rivet 10,

Along the stem 12 of the jaw 5 I provide a series of threads 13 which serve to engage and hold a nut 14. It will be seen that this nut is free to move along the stem without moving the jaw 5. However, the nut also serves to draw the jaw 5 down when it is desired to apply pressure to anything that may be inserted between the jaws of the device. The lower jaw 15 of the wrench is secured near the front marginal section by the pin 16. Usually the lower jaw such as the jaw 15 is secured on the inner side, that is, on the side nearest the stem 12 of the movable jaw, but I find that more satisfactory results are obtained by securing the lower jaw as I have shown. One result, for example of such construction is that I provide a more durable arrangement. It will be seen therefore, that I provide a wrench which is adapted for rough usage, and which, notwithstanding, is simple, the handle, head and heel being a continuous metallic unit. The heel serves as a casing in which the movable jaw slides, and also serves as a hood for the spring 8 protecting the latter against injury; also enabling the disposition of the spring between the frame and the movable jaw which results in a continuous firm pressure of the upper end of the jaw toward the right as shown in Fig. 1.

An advantage in constructing the wrench with a free nut 14 is that it enables more speedy operation inasmuch as the workman may, with his finger, spin the nut 14 which will travel downwardly, for example, in an instant, after which he may, by striking the lower end of the stem 12 with his fist, slide the movable jaw upward to the desired adjusted position. The same speedy operation can be obtained in moving the jaw 5 in the reverse direction.

With this construction, the workman is at liberty to use the wrench as a lever not only in the direction of the arrow, Fig. 1, but in the direction of either arrow, Fig. 2.

It will be noted that the lower nut engaging face of the heel 4 indicated at 17 is curved as shown in Fig. 1, and the top surface of the nut 14 indicated at 18 engaging this laterally curved heel face, enables the nut 18 to move over the curved surface laterally as illustrated in Fig. 1 when the movable jaw 5 is moved laterally, being rotated in a vertical plane as when tightening the wrench onto a pipe or loosening the same. This curved face acting on the nut 14 acts like a cam face when the operator pulling on the wrench handle causes the jaws to tighten onto the pipe or other work.

By referring to Fig. 2, it will be seen that the face 17 is of larger horizontal area than the cross sectional area of the nut 14 with which it contacts. This construction provides a laterally extending flange which is of larger diameter than the nut, and when

the wrench is put down or thrown down on a table or the floor, the nut is maintained substantially out of contact with the floor or table surface, and is prevented from being turned thereby, and the adjustment of the wrench, by this construction, is maintained. Also the larger area of the nut contacting face produces a larger bearing surface for the nut.

It will be noted also that the lowermost thread, 19, on the portion 12 of the jaw 5 is turned so that the nut 14 may not be removed from the end 12 of the said jaw and thereby lost.

What I claim as my invention is—

1. A pipe wrench comprising a handle shank, a casing extending laterally from one end of said handle shank having a channel extending therethrough substantially parallel to said handle shank, a stationary jaw at the end of said shank adjacent said casing, a slideable threaded shank extending through the channel in said casing, a jaw at one end of said slideable shank adapted to cooperate with said stationary jaw, flanges extending outwardly from two opposite sides at the end of said casing adjacent to said handle, the end faces of said flanges being parallel and laterally curved convexly from said handle shank, a spring pressed bearing member enclosed within said casing exerting pressure against the side of said slideable shank adjacent said handle to normally maintain said shank against movement and to tilt the jaw on said shank toward said stationary jaw, and a freely rotatable nut on the end of said threaded shank projecting through said casing adapted to be spun into and out of engagement with the convex face of said flanges, the engagement of said nut with said flanges maintaining said jaw in desired relation while in operation, said slideable jaw being adjustably independent of said nut when said nut is spaced from said flanges, said nut engaging the convex face of said flanges on opposite sides of said shank in any position in which said slideable shank is tilted.

2. A pipe wrench comprising a handle shank, a casing extending laterally from one end of said handle shank having a channel extending therethrough substantially parallel to said handle shank, a stationary jaw at the end of said shank adjacent said casing, a slideable threaded shank, extending through the channel in said casing, a jaw at one end of said slideable shank adapted to cooperate with said stationary jaw, flanges extending outwardly from two opposite sides at the end of said casing adjacent to said handle, a spring pressed bearing member enclosed within said casing exerting pressure against the side of said slideable shank adjacent said handle to normally maintain said shank against movement and to tilt the jaw on said shank toward said stationary

jaw, and a freely rotatable nut on the end of said threaded shank projecting through said casing adapted to be spun into and out of engagement with the lower faces of said flanges maintaining said jaw in desired relation while in operation, said slidable jaw being adjustably independent of said nut when said nut is spaced from said flanges, said nut engaging the lower faces of said flanges on opposite sides of said shanks in ¹⁰ any position in which said slidable shank is tilted.

In witness whereof, I have hereunto signed my name this 23rd day of May, 1922.

WILLIAM O. THEWES.
